US00D925980S

(12) **United States Design Patent** (10) **Patent No.:** **US D925,980 S**
McConnell et al. (45) **Date of Patent:** **** Jul. 27, 2021**

(54) **JUICER ATTACHMENT FOR BLENDER ASSEMBLY**

(71) Applicant: **WHIRLPOOL CORPORATION**,
Benton Harbor, MI (US)

(72) Inventors: **John W. McConnell**, St. Joseph, MI
(US); **Brandon T. Mock**, St. Joseph,
MI (US)

(73) Assignee: **Whirlpool Corporation**, Benton
Harbor, MI (US)

(**) Term: **15 Years**

(21) Appl. No.: **29/747,598**

(22) Filed: **Aug. 24, 2020**

Related U.S. Application Data

(62) Division of application No. 29/723,710, filed on Feb.
10, 2020, now Pat. No. Des. 898,517, which is a
division of application No. 29/689,432, filed on Apr.
30, 2019, now Pat. No. Des. 874,869, which is a
division of application No. 29/639,761, filed on Mar.
8, 2018, now Pat. No. Des. 852,574.

(57) **CLAIM**

We claim the ornamental design for a juicer attachment for
blender assembly, as shown and described.

DESCRIPTION

FIG. 1 is a front top perspective view illustrating a juicer attachment of a blender assembly of the present disclosure; FIG. 2 is a rear top perspective view of the juicer attachment of FIG. 1;

FIG. 3 is a first side elevational view of the juicer attachment of FIG. 1;

FIG. 4 is a second side elevational view of the juicer attachment of FIG. 1;

FIG. 5 is a front elevational view of the juicer attachment of FIG. 1;

FIG. 6 is a rear elevational view of the juicer attachment of FIG. 1;

FIG. 7 is a top plan view of the juicer attachment of FIG. 1; and,

FIG. 8 is a bottom plan view of the juicer attachment of FIG. 1.

The broken lines depict portions of the article that form no
part of the claimed design.
